UNITED STATES PATENT OFFICE.

FERDINAND-CHRISTOPHI VON HEYDEBRAND UND DER LASA, OF NEW YORK,
N. Y., ASSIGNOR TO THE HEYDEBRAND SAFETY WINDOW COMPANY, OF
SAME PLACE.

DESIGN FOR A THUMB-SCREW.

SPECIFICATION forming part of Design No. 26,027, dated September 15, 1896.

Application filed December 21, 1895. Serial No. 572,934. Term of patent 14 years.

To all whom it may concern:

Be it known that I, FERDINAND-CHRISTOPH VON HEYDEBRAND UND DER LASA, a citizen of the United States, residing at New York, 5 in the county and State of New York, have invented and produced a new and original Design for Thumb-Screws, of which the following is a full, clear, and exact description.

The leading feature of my design is a thumb-screw of essentially the configuration and representation shown in the accompanying drawing, which represents an isometric view of a thumb-screw formed according to my design.

15 In the drawing, *a* is an elongated body portion of the thumb-screw, which is cylindrical in cross-section and extends for a considerable portion of the length of the screw, say nearly one-fourth of its length. From this

elongated body portion of the screw projects 20 a head *b*, having a collar *c* of greater extent in diameter than the diameter of the cylindrical body portion *a*. Extending from the body *a* at the opposite end thereof from the collar *c* is a cylindrical shank *d*, which shank is 25 slightly larger than the body and forms a shoulder *e* at the junction with the body and extends about one-fourth the length of the thumb-screw. The shank *d* terminates in a screw *f*. 30

What I claim is—

The design for a thumb-screw substantially as herein shown and described.

FERDINAND-CHRISTOPH
VON HEYDEBRAND U. D. LASA.
